(57) **CLAIM**

The ornamental design for a safety razor, as shown and described.

DESCRIPTION

FIG. 1 is a top isometric view of a safety razor according to the present design;

FIG. 2 is a bottom isometric view thereof;

FIG. 3 is a front view thereof, wherein the rear view is a mirror image thereof;

FIG. 4 is a side view thereof, wherein the opposite view is a mirror image thereof;

FIG. 5 is a top elevational view thereof; and,

FIG. 6 is a bottom elevational view thereof.

The broken lines in the drawings depict portions of the safety razor that form no part of the claimed design.
